UNITED STATES PATENT OFFICE

2,108,495

METHOD OF AND APPARATUS FOR CLEANING COAL

Nils D. Levin, Columbus, Ohio, assignor to The Jeffrey Manufacturing Company, a corporation of Ohio

Application October 11, 1934, Serial No. 747,907
Renewed July 31, 1937

12 Claims. (CL 209—173)

My invention relates to the separation of materials according to their specific gravities and the re-claiming of the solid constituents of the separating medium, and one of the objects of my invention is the provision of an improved method of separating coal from its impurities by increasing the efficiency of operation.

Another object of the invention is to provide improved apparatus for reclaiming the solid constituents of the separating medium for gravity separation of impurities from coal.

A further object of the invention is the preliminary treatment of raw coal or run of mine coal for gravity separation of impurities from the coal employing insoluble material mixed with water so that when such coal impurities are removed from the separating medium a minimum amount of such solid constituents will be taken out of said medium.

A further object of the invention is the provision of a system of coal cleaning apparatus comprising separating mechanism, washing mechanism, reclaiming mechanism and automatic means for maintaining the liquid in the washing mechanism at a predetermined level.

More particularly it is the object of the present invention to provide improved apparatus for cleaning coal and carrying out an improved method therewith to reduce the expense of operation to a minimum by enabling the use of insoluble granular materials in their natural states and without comminution, in the separating medium, and in the washing of the separated coal reclaiming such solid materials as may adhere thereto upon emerging from the separating medium.

Other objects of the invention will appear hereinafter, the novel features and combinations being set forth in the appended claims.

In the accompanying drawings,

Figs. 1 and 2, placed end to end, illustrate apparatus including a separating tank for cleaning coal and for washing the same successively in a series of washing tanks;

Fig. 3 illustrates apparatus including a tank for immersing the raw coal or run of mine coal before it is conveyed to the separating tank, the latter being also shown connected to the series of washing tanks similar to those shown in Figs. 1 and 2;

Fig. 4 is a diagrammatic plan view showing the arrangement of the tanks illustrated in Fig. 3, together with settling tanks and mixing storage tanks;

Fig. 5 is an elevational view illustrating the apparatus shown in Figs. 1 and 2;

Fig. 6 is a diagrammatic plan view of the apparatus shown in Fig. 5, connected to a mixing tank, supply tank and settling tanks;

Fig. 7 is diagrammatic view illustrating conveying apparatus which may be used for removing sediment from the settling tanks shown in either Fig. 4 or Fig. 6;

Fig. 8 is a diagrammatic elevational view of the system shown in Fig. 4, to illustrate the relative elevations of the various tanks;

Fig. 9 is a wiring diagram to illustrate the automatic float control of the pump for replenishing water in the washing tanks; and

Fig. 10 is a curve illustrating a method of adapting a separating medium which will retain a maximum amount of its solid constituents, so as to reduce the amount of such solid constituents which will be carried out with the separated coal into the washing tanks for recovery in the system shown in Fig. 4 or in the system shown in Fig. 6.

In Figs. 1 and 2 I have shown a supporting frame 11 on which are mounted the separating tank 12 and the series of washing tanks 13, 14 and 15. The raw or run of mine coal may be introduced into the hopper 16, as shown in Fig. 1, in the bottom of which the discharge of the coal is regulated by the vertically slidable gate 17. The separating medium, comprising natural clay and granular sand in its natural state mixed with water and an electrolyte, as hereinafter more fully explained, may be of varying depth in the tank 12 according to conditions. The impurities which sink in the separating medium are received by the conveyor 18 comprising the flights 18, 19. These flights are adapted to travel in the direction of the arrow 20 to convey the impurities, such as slate, to the chute 21 from which such impurities are delivered to the endless belt conveyor 22.

The coal which is capable of floating on a separating medium in the separating tank 12 is crowded toward the left, as viewed in Fig. 1, by the incoming raw coal, and such separated coal is received by the conveyor 23, comprising the flights 24, 25. The cleaned coal is conveyed upwardly along an incline in the direction of the arrow 25 where it is discharged into the tank 13 in which a deflector plate 26 guides the coal to the conveyor 27 comprising the flights 28, 29.

Inasmuch as the washing tank 13 is filled with water, the cleaned coal will tend to sink therein and consequently it is desirable to provide an inclined plate 29 for the flights 28 so that coal which reaches the plate 29 may be scooped from the semi-circular receiving portion 30 to move 55

upwardly along the incline in the direction of the arrow 31 for discharge into the next washing tank 14. Further washing in the tank 14 is effected by the discharge of the coal therein for transfer by the conveyor 32 into the tank 15. In the latter the conveyor 33 transfers the washed coal to the discharge chute 34 from which it flows to the belt conveyor 35 for transfer away from the washing apparatus in the direction of the arrow 36.

At the right-hand end of Fig. 1 is shown in dotted lines the position that the operating electric motor 37 occupies on that side of the frame 11 remote from the sprocket chain gearing 38 which is connected to simultaneously drive all of the conveyors shown in Figs. 1 and 2. The motor 37 is connected by reduction gearing 39 and the sprocket gearing 40 to that end of the shaft 41 remote from the sprocket chain 38. That is to say, the driving connection from the motor 37 is to one end of the shaft 41, and to the opposite end of the latter is connected the endless sprocket chain 38 which in turn is connected to all of the traveling conveyors to drive them simultaneously.

At the upper left-hand end of Fig. 2 is shown an inlet port 42 and at the bottom of the washing tanks 13, 14, and 15 are shown drain pipes 43, 44, and 45. Inasmuch as the separating medium in the separating tank 12 contains natural clay and sand in its natural granular state mixed with water and a very small quantity of electrolyte, a small quantity of the separating medium will adhere to the cleaned coal which is transferred by the conveyor 23 to the tank 13. When the conveyor 27 operates to transfer the coal to the next tank 14, most of the clay and sand is washed from the coal and dispersed in the water in the tank 13 where it settles on the conical bottom so that it may flow through the outlet port 43.

If any clay and sand still remain on the coal when introduced into the tank 13, further washing occurs and the clay and sand may be withdrawn through the port 44, shown in Fig. 2. Still further washing may occur in the tank 15 and the clay and sand eliminated through the outlet port 45. Clean water may be introduced intermittently and continuously through the port 42 for flow into the tank 15 and thence into the tank 14 and from the latter into the tank 13. The upper edges 46 and 47 of the walls or separating partitions 48 and 49 are at lower elevations than the upper edges 50 and 51 of the end walls 52 and 53. Consequently, when the tank 15 is filled it may overflow the edge 46 into the tank 14, and when the latter is filled it may overflow the edge 47 into the tank 13.

Regulation of the flow of the sediment from the conical bottoms of the tanks 13, 14 and 15 through the outlet ports 43, 44, and 45 may be secured by means of the system diagrammatically illustrated in Fig. 6. Manual valves 54, 55, and 56 may be placed in the pipes which lead from the ports 43, 44, and 45 so that each of the tanks 13, 14 and 15 may be individually drained to such an extent as to remove the sediment from the conical bottoms thereof. When any one of the valves 54, 55, 56 is opened the mixture of sediment and water will flow into the pipe 57 which is connected by the branch pipes 58 and 59 to the settling tanks 60 and 61. The latter are at lower elevations than the bottoms of the sedimentation tanks 13, 14, and 15, and flow thereto is controlled by the manual valves 62 and 63.

It is preferred to employ two settling tanks 60 and 61 so that one may be used for sedimenta-

tion while the other is being used for receiving material from any one or more of the tanks 13, 14, 15. For instance, if the valve 62 is closed and the valve 63 is open the tank 60 may be used for sedimentation. During operation of the coal cleaning apparatus including the washing mechanism, it is preferred to close the valves 55 and 56 and regulate the opening of the valve 54 so that as the clay and sand settle in the bottom of the tank 13 it will flow immediately into the settling tank 61, the liquid in the tank 13 being automatically replenished by means of the pump 64 operated by the electric motor 65 under the control of switch mechanism. When the pump 64 operates, the valve 66 is closed and the valve 67 is opened so that water will be withdrawn from the tank 60 into the pipe 42 for flow into the tank 15. After clear water has been obtained by sedimentation in the tank 61, the valve 62 may be opened, the valve 63 closed, the valve 66 opened and the valve 67 closed. Then when the pump 64 operates, clear water will be withdrawn from the tank 61 through the pipe 68 into the pipe 42 and thence into the tank 15.

In Fig. 6, 69 designates a mixing tank in which the clay, sand, electrolyte and water may be thoroughly intermixed while the valve 70 is closed. It is desirable to effect this mixture in a separate mixing tank so that it may be permitted to age by standing in a quiescent condition for a period of approximately twenty-four hours, thereby rendering the electrolyte more efficient in its effect on the clay and sand constituents.

After the separating medium has been aged for a predetermined period of time, the valve 70 may be opened to permit the mixture to flow into the storage or supply tank 71 which is larger in capacity than the tank 69, and from which the medium may flow into the separating tank 12 under the control of the manual valve 72.

In the system illustrated in Fig. 4, mixing and storage tanks are provided as indicated at 73 and 74 which are connected through manual valves 75 and 76 to the pipe 77 which leads to a float controlled valve 78 in the separating tank 12'. When the valve 75 is closed the mixing tank 73 may be used for permitting the mixed ingredients of the separating medium to age. During the aging period the other tank 74 may be used for storing the previously aged mixture so that when the valve 76 is opened, flow will take place automatically from the tank 74 to the separating tank 12' under the control of the float valve 78. Consequently, during the operation of the cleaning and washing mechanism illustrated in Fig. 3, the separating medium carried out from the separating tank 12' by removal of the coal and impurities, will be automatically replenished under the control of the float valve 78. When the valve 76 is closed and the valve 75 is opened the flow will be from the tank 73 into the tank 12'.

In Fig. 8 I have shown the relative elevations of the various tanks, the mixing and storage tanks 73 and 74 being located at such elevations as to permit the separating medium to flow by gravity into the separating tank 12' as permitted by the automatic float valve 78.

The operation of the electric motor 65 for driving the pump 64 may be controlled by means of the electric float switch 79, shown diagrammatically in Figs. 8 and 9. When the water in the tank 15' falls to the level indicated at 80 in Fig. 9, the float 81 will descend sufficiently on its

5 pivot 82 to cause the enclosed mercury switch 83 to connect the conductors 84 and 85 whereupon the solenoid 86 will be energized since it will be connected across the mains 87 and 88. 10 When the switch 89 is closed and the solenoid 86 energized, the latter will effect the closure of the motor switch 90. The motor 65 will then be connected by means of the conductors 91, 92 across the supply mains, and the pump 64 will be permitted to draw clear liquid from one of the settling tanks 60 or 61 through the pipe 42 into the tank 15'. When the water in the tank 15' reaches the level indicated by the dotted line position 93 in Fig. 9, the float 81 will be moved 15 to its dotted line position 81' to effect opening of the switch 78 which will cause de-energization of the solenoid 86 and the dropping of the switch 90 to its dotted line position, thereby cutting off the motor 65 and stopping the pump 64. 20 The operation of the valves 54, 55, 56, 62, 63, 66, and 61, in the system shown in Fig. 8, will be the same as described in connection with Fig. 6. The separating tank 12' in Fig. 8 is provided with a drain valve 94. This valve is opened only when 25 it is desired to drain the separating tank 12'.

By referring to Fig. 3 it will be seen that the tank 95 is provided for containing water into which the raw coal or run of mine coal may be introduced from the chute 96. By means of the 30 conveyor 97 the wetted coal is removed from the tank 95 to the chute 98 for flow into the separating tank 12'. The impurities which sink in the separating medium in the tank 12' are removed by means of the traveling conveyor 18' to the 35 chute 21' and thence to the belt conveyor 99. The motor 37' may be connected by means of the sprocket chain 38' to all of the conveyors in the whole system shown in Fig. 3. The sprocket chain should be driven in the direction of the 40 arrows 100.

The bottom of the tank 95 is preferably conical in shape and is provided with a draining port 101 which is connected to the pipe 102 shown in Fig. 8. The draining of the tank 95 may be controlled at intervals by the valve 103. Although 45 the raw coal is screened and de-dusted before entering the tank 95, the wetting of the coal effects further elimination of the coal dust, and when the water in the tank 95 becomes contaminated with coal dust it may be drained by opening the valve 103 and permitting the sediment to flow into one of the settling tanks 60 or 61. It may also occur in practice that the raw 50 coal introduced into the tank 95 even after screening and de-dusting, has considerable sand and clay adhering thereto which will be washed off by being introduced into the tank 95 and the washed raw coal may be conveyed out of the same by the conveyor 97.

60 The solid materials which are washed from the coal in the tanks 95, 13, 14 and 15 and allowed to settle in the settling tanks 60 and 61 may be removed therefrom by means of the drag conveyors 104, 105, as shown in Fig. 7. These conveyors are operated respectively by the motors 106, 107 in the direction of the arrows 108, 109 to take the sediment from the inclined bottoms 110, 111 to the chutes 112, 113, for flow into the mixing tanks 13, 14. The motors 106, 107 are 65 connected by the sprocket chain gearing 114, 115 to the conveyors 104, 105 to drive the same in the direction of the arrows 108, 109. It should be understood, however, that the conveyors 104, 105 are operated alternately because one of the settling tanks receives the sediment from the wash-

ing tanks while sedimentation is taking place in the other sedimentation tank. The coal dust which may be mixed with the clay and sand can readily be separated therefrom by flotation on a liquid separating medium, and the clay and sand recovered in this manner may be re-used in the mixing tanks 13 and 14. 5

In the co-pending application of applicant and Samuel H. Yost for an Improvement in method of cleaning coal and fluid-separating mediums therefor, Serial No. 747,906, filed Oct. 11, 1934, the preferred separating medium for use in the tank 12 or tank 12' is described and claimed, whereas the present application adds the preliminary step of wetting the raw coal in the tank 95 and also includes the washing of the separated coal after leaving the separating tank, and in addition I have disclosed in Figs. 4, 6, 8, and 9 systems of handling the liquids and solid materials immersed therein. I have also added the 20 curve shown in Fig. 10 to illustrate the tests which may be carried out so as to reduce to a minimum the amount of solid constituents carried out from the separating medium when the cleaned coal and the impurities are removed from 25 the tank 12 or tank 12'.

In the first place it should be understood that the principal object of wetting the raw coal preliminarily in the tank 95 is to fill up the crevices therein so that less of the solid constituents of the separating medium in the tank 12' will adhere to the separated coal and impurities when they are removed from the tank 12'. Inasmuch as the washing system herein disclosed is arranged and operated to obtain 30 the greatest efficiency, the operating medium is so composed as to retain the greatest amount possible of its solid constituents by preventing the removed coal and impurities from carrying out any more than is necessary. In order to 35 fully understand the significance of the curve shown in Fig. 10, it will be necessary to describe the preparation of the separating medium used in the tank 12 in the system shown in Figs. 1, 2, 5, and 6, and in the tank 12' in the system 40 shown in Figs. 3, 4, and 8.

In order to predetermine the specific gravity of the separating medium or mixture to be used in the systems disclosed in the accompanying drawings, the raw coal or run of mine coal to 50 be cleaned is analyzed by methods of sampling, sink and float tests, chemical analyses, etc. Then, depending upon what grade of purity of coal is desired, the specific gravity at which separation should take place, when following my 55 improved methods, is predetermined. The separating medium or mixture is then prepared so that the marketable coal will float in the separating tank 12 or the separating tank 12'.

In preparing the separating medium it is preferred to follow certain definite formulae which from actual tests have given the best results but which may be varied in accordance with conditions. By using one part natural clay and four parts natural sand, by weight, without pulverizing or comminuting either the clay or the sand, and stirring the clay and sand in water, a medium of the desired specific gravity may be obtained with the assistance of well known tests of specific gravities of mixtures of solid granular matter with water. The specific gravity of the sand is approximately the same as that of the clay. 60

The addition of a small amount of a deflocculating agent such as sodium aluminate or sodium 65 70 75

silicate to the mixture of natural clay and natural sand in the water, will cause the clay and sand after being stirred in the water, to remain in suspension for a relatively long period of time, thereby rendering the fluid mixture very efficient in the gravity separation of impurities from coal with little or no agitation of the separating medium.

In gravity separation of impurities from coal, agitation of the liquid hampers the process, and it is therefore desirable to reduce the agitation to a minimum. For instance, when the agitation of the liquid medium is too great, small and flat pieces of slate will follow upward currents and be mixed with the cleaned coal, thereby rendering perfect separation impossible. However, in the use of the conveyors 18 and 23 in the separating tank 12 or the conveyors 18' and 23' in the tank 12', the agitation of the liquid medium is so small as not to disturb the desired separation of impurities from the marketable coal.

If sufficient natural clay is so mixed with water as to finely divide it without comminution or pulverization, a liquid medium may be obtained of sufficient specific gravity to float coal, but it will be found to be too thick or viscous for practical use. However, by adding the proper amount of electrolyte such as sodium aluminate or sodium silicate, the mixture will be rendered more fluid without affecting the specific gravity. After testing various forms of natural clay, one form of fireclay was found that could be used in practice without the addition of sand, but this separating medium was not found to be very efficient. In other words, while satisfactory results may be obtained by the use of a mixture of a certain clay and water without sand but including the addition of a small amount of sodium aluminate or sodium silicate, the best results are obtained by the inclusion of natural sand in the mixture. The use of natural clay alone in most cases decreases the fluidity of the mixture to such an extent as to slow down the separating process as compared with the speed of operation when natural sand is included in the mixture, because the inclusion of the sand increases the fluidity of the separating medium. Clay is an argillaceous material which is composed of particles in a finely divided state which when mixed with water may be dispersed throughout the volume thereof, while sand is a non-argillaceous granular material usually found in its natural state as silica. The particles of clay in their natural state are relatively fine and the granules of the natural sand are relatively coarse. Both of these materials are available at low cost almost anywhere in this country, and by reason of the use of the electrolyte, preferably sodium aluminate or sodium silicate, no grinding or pulverizing of either the natural clay or the natural sand is necessary in the formation of the separating medium used in my systems illustrated in the accompanying drawings.

The sodium aluminate or sodium silicate may be a de-flocculating agent so far as the clay suspension is concerned, but the suspension of the sand may perhaps be best explained by the fact that the sodium silicate or sodium aluminate acts as an electrolyte to produce electrical charges in the clay particles to hold in suspension for a relatively long period of time the natural sand granules in intimate relation with the dispersed clay in a homogeneous separating medium.

In the formation of the separating medium by mixture of the ingredients in the mixing tanks 13 and 14 of Figs. 4 and 8, or in the mixing tank 69 of Fig. 6, it is important to follow certain definite formulae according to conditions. It has been found from actual tests that under certain conditions the amount of sodium silicate or sodium aluminate for the best results in maintaining the clay and sand in suspension for a relatively long period of time without agitation, 10 should be approximately .8% of the weight of the clay. By means of tests hereinafter explained the critical proportions may be ascertained. That these proportions are critical is evidenced by the fact that in the tests referred to above, 15 doubling the amount of the electrolyte caused a rapid settling of the clay and sand in a mixed mass without layering.

In order to explain the procedure by which certain definite formulae may be arrived at for obtaining the best results in the use of a separating medium for the cleaning of coal, certain actual tests have been carried out and the results observed. By mixing one part Minford silt (argillaceous material in its natural state) and four 25 parts of white coarse sand by weight, and adding sufficient water to obtain a specific gravity of 1.55, after stirring into the mixture .8% of sodium aluminate, no sediment of the solid insoluble ingredients was shown after a period of 30 twenty-four hours.

When a mixture having a specific gravity of 1.55 was made of one part Minford silt and five parts sand and .8% of sodium aluminate in water, a very slight settling was observed after a 35 lapse of twenty-four hours, but in similar mixtures having one part silt and six parts sand, and one part silt and seven parts sand, pronounced settling occurred after a lapse of twenty-four hours, but the settled mass was a very soft 40 intermixture of silt and sand such as not to interfere with the restarting of the conveyor mechanism shown in the separating tank 12 in Fig. 1 or in the separating tank 12' in Fig. 3. Upon restarting the conveyor mechanism through such 45 settled mass, only a slight mechanical agitation was necessary to recondition the separating medium, but the homogeneous condition of the medium could be obtained only by sufficient agitation. The water used in the foregoing tests was that 50 from a city hydrant in Columbus, Ohio.

When Sandusky Foundry sand (10% clay) was used in tests with Minford silt, there appeared to be no appreciable settling after a lapse of twenty-four hours, even when the ratio of the ingredients 55 was one part silt to 8 parts of sand, by weight.

Fireclay and white sand mixtures did not prove to be as suitable as silt and white sand mixtures. Fireclay and Sandusky sand mixtures showed no appreciable settling after standing twenty-four 60 hours at a ratio including one part fireclay to six parts Sandusky sand.

Inasmuch as it consumes some time for the progressive deflocculating action of the sodium aluminate to take place, it is preferred to age the 65 mixture for a period of at least twenty-four hours. This can readily be done in the systems shown in Figs. 4 and 8 where two mixing tanks are included for alternate use. When the Minford silt is used with a mixture containing city 70 water, it was found that the minimum deflocculation was effected by the use of sodium aluminate over a range of .6% to .9% as to the amount of sodium aluminate relative to the weight of the clay. After aging the mixture in the tank 13 or 75

the tank 74, the maximum deflocculation is definitely indicated at approximately .8% with a pronounced reaction over a range of .8% to one percent.

5 The percentage of the solid ingredients in suspension in the separating medium is much greater for Minford silt than for fireclay and the duration of the suspension is also much longer for the Minford silt. This is probably due to the difference in the size of the particles in the two clays.

10 The Minford silt is the better suspending agent of the two clays tested and the Sandusky sand, a relatively fine sand, is the one more readily maintained in suspension of the two sands tested.

15 The permissible sand variation for a given specific gravity between 1.5 and 1.6 was found to be 25 percent for practical operations. With the less favorable sand, the permissible electrolyte variation plus or minus from the optimum 20 point of .8 percent was found to be 12 percent. That is to say, the best results are obtained with .8 percent of electrolyte with a permissible range from .6 percent to nearly one percent.

25 Inasmuch as Minford silt is composed of finely divided particles of argillaceous material and Sandusky Foundry sand is relatively fine, eight parts of sand could be held in suspension in the water having in solution a small quantity of sodium aluminate, so that there would be no appreciable settling after a lapse of twenty-four hours. The highest specific gravity of the mixture can therefore be obtained when the argillaceous material is in a naturally finely divided state and the sand is relatively fine.

30 Bentonite is another form of argillaceous material which is found in nature in a finely divided state and has the property of cooperating with an electrolyte to hold ten parts of fine sand in suspension in a separating medium over a relatively long period of time without agitation.

35 Fireclay is composed of particles in a finely divided state but not as fine as either silt or bentonite. However, fireclay was found to coact with the electrolyte to hold in suspension six 40 parts of Sandusky sand by weight in a suitable separating medium because no appreciable settling occurred after standing for twenty-four hours.

45 It will thus be seen that the tests which were conducted showed that the selection of the finest argillaceous material in its natural state and the selection of the finest sand in its natural state enabled the electrolyte sodium aluminate to act to hold in suspension the greatest amount of solid ingredients in the separating medium over a long period of time without appreciable settling, thereby demonstrating the practicability of avoiding agitation although solid insoluble ingredients are used as found in nature without comminution or pulverization. In this manner a separating medium of relatively high specific gravity may be obtained. Such separating medium would have maximum buoyancy and would permit the adding of more water to obtain the desired specific gravity of the mixture. Therefore the finer the solid materials the greater may be the fluidity for a given specific gravity.

50 However, it was found from actual tests that the finer the solid ingredients in the separating medium the greater would be the carry-off of such materials with the separated coal and with the impurities separated and removed. For instance, the minimum carry-off of solid ingredients from a separating medium composed of a silt and Sandusky sand (1 part silt plus 4 parts

5 Sandusky sand by weight) in water having in solution .8% sodium aluminate (the separating medium having the specific gravity of 1.53) was about 40 pounds per ton of raw coal treated, whereas with a separating medium having a specific gravity of 1.53 and composed of 1 part silt and 4 parts white coarse sand in water having in solution .8% sodium aluminate, the carry-off was found to be 26 lbs. per ton of raw coal treated. Even fireclay gave better results when mixed with 10 coarse white sand than when mixed with the fine Sandusky sand. With a separating medium having the specific gravity of 1.53 and composed of 1 part fireclay and 6 parts white sand by weight in water having in solution .8% sodium aluminate 15 the carry-off was found to be 18 lbs. of solid ingredients per ton of raw coal treated, whereas with a separating medium composed of 1 part fireclay and 6 parts Sandusky sand by weight in water having in solution .8% sodium aluminate 20 the carry-off was found to be 20 lbs. of ingredients per ton of raw coal treated.

25 While therefore theoretically it may be desirable to have both of the ingredients in finely divided condition, it is more practical and economical to have one relatively fine as found in nature and the other relatively coarse and also as found in nature.

30 Ageing of the mixture of sodium aluminate, water, clay and sand greatly reduces the amount 30 of carry-off in the treatment of coal to separate the impurities therefrom. The proper balance may readily be obtained in practice. Fireclay-white sand mixtures over a range of $\frac{1}{4}$ to $\frac{1}{6}$ all settled considerably faster than silt-white sand 35 mixtures. But fireclay-Sandusky sand mixtures showed no appreciable settling at ratios up to and including $\frac{1}{6}$.

35 Inasmuch as the argillaceous material and the sand varies in nature in various parts of the 40 country the correct formula for the separating medium to suit conditions depends upon the clay suspension, the sand suspension, and the clay-sand adherence resulting from contact with smooth imporous surfaces. The related determinations to be made are (1) the concentration of the electrolyte such as sodium aluminate or sodium silicate to clay which produces the maximum deflocculation of the clay, (2) the effect of varying the sand-clay ratios upon the duration 45 of the suspension and the homogeneity of the suspended mixture, (3) the effect of varying the sand-clay ratio upon the adherence value, and (4) the effect upon the foregoing of varying the type of clay and sand used in the mixtures. 50 The most efficient formulas will be those which maintain suspension of both ingredients over such a length of time as to render agitation unnecessary, and which will result in a minimum carry-off of the solid ingredients—clay and sand—from the separating medium. The clay and sand should be available as found in nature without screening or comminution or pulverization, and therefore the process may be carried out anywhere at a very low cost in materials and maintenance. Such sand, of course, includes 55 silica sand. Where solid materials are to be used as sand, by crushing ganister, quartz, etc., the granules need be no smaller than those of ordinary silica sand.

60 The conclusions from the actual tests made are as to the solid insoluble ingredients, that Sandusky sand, a relatively fine sand, is not as favorable as coarser sands unless the matter of 65 suspension becomes a controlling factor and re- 70 75

quires its use at lower specific gravities. In other words, the colloidal clay acted upon by the electrolyte has the property of keeping in suspension for a long period of time the finer sands. The 5 tests also showed that silt gave more favorable results than fireclay. Silt in its natural state is composed of particles more finely divided than the fireclay. The ageing of the mixture for a period of at least twenty-four hours enabled better 10 results to be obtained. The variation of the specific gravity of the mixture can be controlled by varying the proportion of the water. The fluidity of each of the mixtures tested was sufficient to permit free settling of the impurities 15 during flotation of the cleaned coal, since the consistency or mobility of the mixture is not such as to interfere with the rapid operation of the separating process.

It has been found from actual tests that sodium 20 silicate is preferable when the water is well water or hard water, while sodium aluminate is preferable for the hydrant water of the city of Columbus, Ohio, which water has been treated chemically to purify the same. However, either sodium 25 silicate or sodium aluminate may be used as the suspension agent in either hard water or soft water.

Sodium silicate is usually obtainable in liquid 30 form, whereas sodium aluminate is in powdered or desiccated form, the latter being more conveniently handled than liquid sodium silicate. Both sodium silicate and sodium aluminate can be obtained at very low cost. For instance, in the 35 formula using one part natural clay and four parts natural sand with .8% of sodium aluminate, the cost of the latter in certain localities is only about 1/250th of the cost of the clay and sand combined. That is to say, in a separating medium having one part clay, four parts sand and .8 40 percent sodium aluminate, the cost of the sodium aluminate required is only .4 percent of the cost of the clay and sand combined. This cost of the electrolyte is so low that no attempt need be made in practice to reclaim any of it that clings 45 to the cleaned coal as it passes through the washing tanks shown in the accompanying drawings.

The formula for making up the mixture or separating medium used in our method of cleaning 50 coal differs with the materials available to serve as the insoluble solid ingredients. The clays which are useful in my method, while having the general characteristics of kaolinite are not necessarily pure clays but would fall under the general 55 classification of shale, surface clay, silt and fireclay. These types are widely distributed and readily available in various parts of this country, and each is useful in the process in its natural state.

60 The essential characteristics of the argillaceous material in the method of separating coal from its impurities, are those having the property of being dispersed or deflocculated by the electrolyte and after being dispersed or deflocculated, 65 having the property of maintaining in suspension the desired quantities of sand or other inert granular material.

Such properties in my separating medium used 70 in my improved method of cleaning coal, may be readily determined by simple tests which may be carried out wherever clay and sand are found in various parts of the country or wherever it is desired to follow such method. I have set forth 75 formulae for most efficient operation in certain localities but such formulae may be varied in

various parts of the country in accordance with the nature of the natural clays and the natural sands available. I will therefore set forth the procedure that should be adopted to arrive at the most efficient results for various kinds of 5 clays and sands.

The procedure is to mix the clay and water to be used, the weight of the clay being about 25 percent of that of the water. This mixture is placed in a series of beakers and to each beaker 10 is added a different amount of electrolyte such as sodium aluminate or sodium silicate. After the mixture in each beaker is stirred it is allowed to stand for forty-eight hours and the one that shows the best suspension of clay is the mixture 15 that should be selected. If the clay cannot be maintained in suspension in any of the beakers it is not a suitable form of clay.

When a suitable clay is found by following the tests with the electrolyte, the mixture of clay 20 and electrolyte is introduced into a series of beakers, and sand in various proportions is added to the various beakers. The combined weight of the sand and clay should be the same in each beaker. One beaker may contain clay alone and the other 25 one part clay and two parts sand, one part clay and three parts sand, etc. Some clays such as bentonite, have the property of carrying ten parts of sand when the electrolyte sodium aluminate is used in a suitable separating medium in 30 my method of cleaning coal. It should also be understood that sufficient water is added to the various beakers to obtain the specific gravity required for the desired coal separation.

After the mixtures in the beakers containing 35 the sand have stood for twenty-four hours, observations are made and those beakers eliminated which show settling of the sand at the bottoms of the beakers.

After selecting the most efficient mixture by 40 proceeding with the tests outlined, the next test to be made is to determine the amount of the mixture that will be carried away with the coal when removed from the separating tank to the first washing tank. For this purpose a piece of 45 polished glass triangular in shape and having sides each four inches long may be dipped into the mixture and withdrawn; by weighing the glass before dipping and after, the weight of the mixture that adheres to the glass can be calculated. The mixture that carries off the least amount of separating medium is the most desirable to be used in practice. For instance, in actual tests it was found that for each one-tenth of a gram per square inch carried off by the testing 55 glass, there will be seventeen (17) pounds of mixture carried off by a ton of separated coal.

These tests were made by dipping the glass plate into the beaker mixtures and weighing while wet. The weights were calculated as the 60 weight of the mixture adhering to each square inch of surface of the plate. Instead of using glass plates imporous card-board squares may be used for immersion in the beaker mixtures but it will be found that less solid material will 65 adhere to the card-board than to the glass plate.

In such carry-off tests of beaker mixtures, a curve may be plotted from the results obtained. For instance, in connection with actual tests made with a series of beaker mixtures in which 70 the amount of sodium silicate ranged from zero to 3.6 percent by weight of clay in the fluid, the plotted curve will show a gradual decrease in the amount of clay carried out on a card until the percentage of sodium silicate is about 1.3 75

or 1.4, after which the increase of the percentage of sodium silicate increases the amount of clay carried out on a card. The clay used was a form of fireclay having a pH value of 5. After 5 permitting the beaker mixtures to stand for twenty-four hours after adding the electrolyte and stirring the mixture, it was found that the clay remained in suspension the longest in the beaker having 1% of sodium silicate by weight of 10 clay in the mixture, and the tests further showed that the range for best results would be between 1% and 1.4% of electrolyte. The carry-off tests of clay mixtures also enabled the plotted curve in Fig. 10 to show pounds of clay per ton of coal 15 that would be carried out of the medium during the coal separating process. For instance, in the tests just described where the best results would be obtained with the electrolyte 1.3% by weight of clay in the mixture, the least amount of 20 clay would be carried out on the card and would represent about 30 pounds of clay per ton of coal.

As above explained, there is a permissible range in the use of the proportions of the ingredients in the water for maintenance of the clay and 25 sand in suspension over relatively long periods of time. In the beaker tests there may therefore be various mixtures which would be suitable so far as maintenance of the clay and sand in suspension is concerned, but by following the polished glass test the best separating medium may 30 be obtained so that a minimum amount of the separating medium will be carried away with the separated coal by the conveyor 23 and a minimum amount will be carried away when the impurities 35 at the bottom of the separating tank are conveyed out of the tank by the conveyor 48. It should be understood that during the operation of the separating apparatus the intermixture of the ingredients is so thorough that when the 40 cleaned coal and impurities are removed from the separation tank, the medium that clings to the removed materials is about the same in its proportions of constituents as the medium that remains in the tank. The medium in the tank 45 therefore remains as to specific gravity and efficiency, the same as when first introduced and the replenishment of the medium in the separating tank is by means of the same mixture as that selected by means of the foregoing tests.

50 Inasmuch as it is important to reduce to a minimum the amount of solid ingredients carried off from the separating medium and it is also important to maintain suspension of the solid ingredients in the separating medium, the curve 55 shown in Fig. 10 after being plotted from the tests above outlined, may be used to determine the most practical percentage of sodium silicate or sodium aluminate in the separating medium. For instance, since the best results from the 60 tests indicate from .6% to .9% of sodium silicate by weight of clay and the curve shown in Fig. 10 indicates 1.3% of sodium silicate by weight of clay, approximately one percent of sodium silicate by weight of clay could be used in practice 65 to the extent that the amount of solid ingredients that would be carried out by the separated coal and impurities from the separating medium will be approximately 32 lbs. per ton of raw coal treated.

70 Inasmuch as the percentage of sodium silicate or sodium aluminate for suspension purposes is critical as above explained, the region to the left of the lowest point of the curve of Fig. 10 should be relied on to determine the percentage of electrolyte for obtaining the desired results both as to

suspension of the solid ingredients in the separating medium and as to reduction to the minimum of the solid ingredients carried off from the separating medium.

It should be particularly noted by reference to Figs. 4, 8, and 9 that the operation of separating coal from the impurities may be carried on automatically over an extended period of time. For instance, if the tank 73 acts as a storage tank while the valve 76 is closed and the valve 75 5 open, the automatic float valve 78 will maintain the depth of the separating medium in the separating tank 12' at a predetermined level. At the same time the settling tank 60 may have clear liquid therein so that when the valve 66 is closed 10 and the valve 67 is open the float controlled switch 79 will effect intermittent automatic operation of the pump 64 to replenish water in the tank 15' for flow successively into the tanks 14 15 and 13. This is true whether the valve 54 is open 20 or not but will take place oftener if the valve 54 is partially open and the valve 62 is closed when the valve 63 is open. There will then be a continuous draining of settling material from the bottom of the tank 13 to the settling tank 61 25 while the automatically controlled and operated motor 64 replenishes the water in the tanks 15', 14 and 13. When sediment is removed from either of the settling tanks 60 or 61 it may be delivered by means of the chutes 112, 113 directly 30 to the mixing tanks 73, 74, as shown in Fig. 7.

That is to say, when the system shown in Fig. 4 is in operation, the valve 94 is kept open continuously. The extent of opening of the valve 94 is regulated so that the water in the last tank 15' 35 is practically clear. If the water in the second tank 14 is practically clear, too much water is being used in the automatic circulating system which indicates that the valve 94 should be partially closed. On the other hand if the water in 40 the last tank 15' is discolored, the valve 94 should be moved toward open position. The valves 55 and 56 are kept closed during normal operation and are opened for draining purposes only about once in a shift of about eight hours and then 45 closed again.

It is also important to note that in the apparatus used in my system and for my methods the liquids are substantially quiescent. This is particularly true in the separating tank the bottom 50 of which is entirely closed during operation and in which no special means is provided for agitating the separating medium. The conveyors for removing the separated coal and impurities are 55 operated at a relatively slow speed and may be arranged either as shown in Fig. 1 or as shown in Fig. 3.

While I prefer to include the preliminary wetting of the raw coal for the reasons hereinbefore explained this is not always necessary or desirable 60 from the standpoint of economic operation. The raw coal wet or dry, is fed into a quiet pool or separating bath in the separating tank and the separated coal is then moved upwardly to a predetermined height from which 65 it is dropped by gravity into the first washing tank. This operation is entirely automatic and the impact against the water assists materially in washing from the coal the solid ingredients carried over from the separating medium. However, 70 when the coal strikes the water the latter yields to prevent breakage of the coal.

In some localities the sand and clay may be obtained at such low cost that the reclaiming of the same may not be desirable in which event, 75

- however, it may still be economical to retain the water circulation for the washing tanks. That is, the sedimentation steps may be carried out for the purpose of obtaining clear water to replenish 5 that used in the washing tanks and this may be done automatically. In fact, all of the apparatus shown in the drawings may be retained if desired, although the sediment from the sedimentation tanks is discarded.
- 10 Obviously those skilled in the art may make various changes in the details and arrangement of parts without departing from the spirit and scope of the invention as defined by the claims hereto appended, and I therefore wish not to be 15 restricted to the precise construction herein disclosed.

Having thus described and shown an embodiment of my invention, what I desire to secure by Letters Patent of the United States is:

- 20 1. In apparatus for separating coal from its impurities, and washing the separated coal, the combination with a wetting tank, of a separating tank, a washing tank, two sedimentation reclaiming tanks adapted to be used alternately, two mixing 25 and storage tanks either adapted to be used as a mixing tank while the other is being used as a storage tank, means connected between the last-named tanks and said separating tank to maintain the separating medium in the last-named 30 tank at a predetermined level, means affording flow of settled solids from the washing tank to either of said sedimentation tanks, automatic mechanism for pumping water from either sedimentation tank to said washing tank to maintain 35 the depth of water in the latter at a predetermined level, and conveyor mechanism associated with the separating tank for removing impurities and separated coal therefrom, and conveyor mechanism for the washing tank to remove the 40 washed coal therefrom.
2. In apparatus for separating coal from its impurities, the combination with a separating tank, of a washing tank, a sedimentation tank, conveyor mechanism for removing separately the 45 separated coal and impurities from the separating tank, conveyor mechanism for removing separated coal from the washing tank, means for effecting transfer of settled solids from the washing tank to said sedimentation tank, and automatic pump mechanism for pumping water from the sedimentation tank into said washing tank to maintain the depth in the latter at a predetermined 50 level.
3. The method of cleaning coal which comprises mixing a separating medium comprising insoluble granular material and a deflocculating or dispersion agent, storing and aging said medium, introducing said separating medium into a separating tank, introducing raw coal into said separating medium while in a quiescent condition in said separating tank thereby separating the coal from the refuse, removing the refuse from said tank, removing the coal from said tank while leaving the separating medium therein except for 55 particles which adhere to said coal, washing said coal to remove the adhering separating medium therefrom, and recovering the removed separating medium to be used again.
4. The method of cleaning coal which comprises mixing a separating medium comprising insoluble granular material, clay, and a deflocculating or dispersion agent, storing and aging said medium, introducing said separating medium into a separating tank, introducing raw coal into said 60 separating medium while in said separating tank

thereby separating the coal from the refuse, removing the refuse from said tank, removing the coal from said tank while leaving the separating medium therein except for particles which adhere to said coal, washing said coal to remove the 5 adhering separating medium therefrom, and recovering the removed separating medium to be used again.

5. The method of cleaning coal which comprises mixing a separating medium comprising sand, clay and a deflocculating or dispersion agent, storing and aging said medium, introducing said separating medium into a separating tank, introducing raw coal into said separating medium while in a quiescent condition in said separating tank thereby separating the coal from the refuse, removing the refuse from said tank, removing the coal from said tank while leaving the separating medium therein except for particles which adhere to said coal, washing said coal to remove 10 the adhering separating medium therefrom, and recovering the removed separating medium to be used again.

6. The method of cleaning coal which comprises mixing a separating medium comprising clay, sand and a relatively small amount of a deflocculating or dispersion agent, storing and aging said medium in a quiescent state, introducing said aged separating medium into a separating tank, introducing raw coal into said tank, and separately removing the materials which float and those which sink.

7. The method of cleaning coal which comprises mixing a separating medium comprising sand and a relatively small amount of a deflocculating or dispersion agent, storing and aging said medium in a quiescent state, introducing said aged separating medium into a separating tank, introducing raw coal into said tank, and separately removing the materials which float and those which sink.

8. The method of cleaning coal which comprises mixing a separating medium comprising clay and a relatively small amount of a deflocculating or dispersion agent, storing and aging said medium in a quiescent state, introducing said aged separating medium into a separating tank, introducing raw coal into said tank, and separately removing the materials which float and those which sink.

9. In a system of separating impurities from raw coal, the combination with a separating tank, of means comprising a float controlled valve for maintaining the depth of separating medium in said tank at a predetermined level, a washing tank, a settling tank, means for controlling draining of sediment from said washing tank to said settling tank, means comprising a pump for drawing liquid from above the sediment in said settling tank and delivering said liquid to said washing tank, a motor for operating said pump, automatic means comprising a float in said washing tank for controlling said motor to operate said pump to maintain the depth of liquid in said washing tank at a predetermined level, means for removing separated impurities from said separating tank, and means for moving cleaned coal from said separating tank into said washing tank and then out of the latter.

10. In a system of separating impurities from raw coal, the combination with a wetting tank adapted to contain water, of a separating tank adapted to contain a separating medium, means for introducing raw coal into the water in the wetting tank and then deliver such wetted coal

into the medium in said separating tank, a washing tank adapted to contain water, means for removing the separated impurities from said separating tank, means for removing cleaned coal from said separating tank and moving it into and out of the water in said washing tank, a settling tank, means for effecting drainage of sediment from said wetting and washing tanks into said settlement tank, and automatic means for drawing water from above the sediment in said settling tank and introducing such water into said washing tank to maintain the depth of water in the latter at a predetermined level.

11. In a system of separating impurities from raw coal, the combination with a separating tank adapted to contain a separating medium comprising granular material held in suspension by a dispersion agent, means for removing from said tank the separated impurities, a settling tank, means comprising a valve for controlling drainage to said settling tank of impurities settled to the bottom of said separating tank, a washing tank adapted to contain water, means for removing cleaned coal from said separating tank and moving such cleaned coal into and out of the water in said washing tank, means comprising

a valve for controlling drainage of sediment from said washing tank into said settling tank, and automatic means for controlling the drawing of liquid from above the sediment in said settling tank and introducing said liquid into said washing tank to maintain the depth in the latter at a predetermined level. 5

12. In a system of separating impurities from raw coal, the combination with a separating tank adapted to contain a separating medium, of a 10 plurality of washing tanks each adapted to contain water, overflow means between each washing tank and the next adjacent washing tank, mechanism for removing separated impurities from said separating tank, a settling tank, means 15 for controlling flow of sediment from said washing tanks to said settling tank, means for removing cleaned coal from said separating tank and then moving such cleaned coal into and out of the water successively in said washing tanks, and 20 automatic means for drawing water from above the sediment in the settling tank and introducing such water into one of said washing tanks to the level of said overflow means to effect a uniform predetermined depth in all of the washing tanks. 25

NILS D. LEVIN.
